(57) **CLAIM**

The ornamental design for a food packaging with vehicle ornamentation, as shown and described.

DESCRIPTION

FIG. 1 is a top, front, and right-side perspective view of a food packaging with vehicle ornamentation showing my new design;

FIG. 2 is a front view thereof;

FIG. 3 is a rear view thereof;

FIG. 4 is a left-side view thereof;

FIG. 5 is a right-side view thereof;

FIG. 6 is a top view thereof; and,

FIG. 7 is a bottom view thereof.

Broken lines are used to illustrate portions of the food packaging with vehicle ornamentation that form no part of the claimed design.
